UNITED STATES PATENT OFFICE.

FRED JOSEPH MOSER, OF KANE, PENNSYLVANIA.

ANCHOR FOR TUBINGS FOR GAS-WELLS.

1,283,864.

Specification of Letters Patent.

Patented Nov. 5, 1918.

Application filed January 8, 1917. Serial No. 141,231.

To all whom it may concern:

Be it known that I, FRED J. MOSER, a citizen of the United States, residing at Kane, in the county of McKean and State of Pennsylvania, have invented new and useful Improvements in Anchors for Tubings for Gas-Wells, of which the following is a specification.

This invention relates to improvements in an anchor for tubings for gas wells and consists in certain improvements in the construction thereof as will be hereinafter fully described and pointed out in the claim.

With gas wells of very high pressure it is necessary to anchor the tubing and also desirable to have the fitting capable of drawing off the salt water or other material from the well, as well as for conveniently connecting the well for use.

In my Patent #1,150,875, dated August 24, 1915, I have shown a device of this character and the present invention is in the nature of an improvement of that device.

The invention is illustrated in the accompanying drawings as follows:—

Figure 1 shows a plan view of the device.

Fig. 2 a side elevation of the device.

Fig. 3 a section on the line 3—3 in Figs. 1 and 2.

Fig. 4 a view similar to Fig. 2 with an alternative form of anchor bolts.

1 marks a casing, 2 a tubing, 3 a casing head, 4 a gland in the casing head through which the tubing extends and 5 the anchor fitting. The anchor fitting has the laterally extending wings 6 through which the bolts 7 extend, the bolts being secured as shown in Fig. 2 to the casing head. As shown in Fig. 4 the bolts 7^a are provided with the turn buckles 7^b and are secured to timbers as 18^a, the timbers being properly anchored in the ground or otherwise.

The anchor fitting has a connection 2^a into which the tubing 2 extends and a discharge

connection 8 above the connection 2^a. A 45 nipple 9 is screwed into the connection 8 and a valve 10 is arranged on the nipple. A lateral connection 11 is formed on the fitting. A nipple 12 is screwed into this connection and a valve 13 provided which valve is ordinarily connected with the line 13^a. A connection 14 is provided opposite the connection 13. This may be of small size, or large size provided with a plug 15. A pipe 16 leads to an indicator or gage 17 which may be used if desired.

In my former construction there was no water discharge connection directly opposite the tubing connection. These anchor fittings are particularly useful in high-pressure wells. If a lateral discharge is used the lateral thrust when the gas or water is discharged to the atmosphere may be sufficient to bend the pipe and injure the connection. By making the water discharge opening directly opposite the tubing connection this difficulty is obviated and at the same time a convenient connection is made laterally to the line. In operation, when it is desired to blow out the well, the valve 13 is closed and 70 the valve 10 opened and when it is desired to close the discharge and open the line the valve 10 is closed and the valve 13 opened.

What I claim as new is:—

In combination with a casing head and 75 well tubing extending through the casing head of an anchor fitting provided with integral anchor wings and with oppositely disposed openings, one of which is secured to and in alignment with the tubing and the 80 opposite of which forms a water discharge and with side openings for a gas discharge and pressure gage attachment, and anchor bolts operating on the anchor wings for securing the tubing in the casing head.

In testimony whereof I have hereunto set my hand.

FRED JOSEPH MOSER.
